UNITED STATES PATENT OFFICE.

JOSEPH JUNGBLUTH, OF ERIE, PENNSYLVANIA.

COCK FOR WASH-BASINS.

SPECIFICATION forming part of Letters Patent No. 314,943, dated March 31, 1885.

Application filed April 12, 1884. (No model.)

To all whom it may concern:

Be it known that I, JOSEPH JUNGBLUTH, of Erie, in the county of Erie and State of Pennsylvania, have invented certain new and useful Improvements in Cocks for Wash-Basins, of which the following is a specification.

This invention has reference to an improved three-way cock for wash-basins, by which the water-supply, overflow, and discharge is accomplished to the exclusion of sewer-gas.

In the accompanying drawings, Figure 1 represents a side elevation of a wash-stand with my improved three-way cock. Figs. 2, 3, 4, and 5 are vertical sections of the same, showing the three-way cock in different positions, respectively, for supplying the water to the basin, shutting off the supply, discharging the water, and the connection with the overflow; and Fig. 6 is a top view of the three-way cock.

Similar letters of reference indicate corresponding parts.

A in the drawings represents the basin of a wash-stand provided with the usual outlet-pipe G at its bottom; B, a three-way cock or valve; C, the supply-pipe, and D the waste or discharge pipe, which pipes are connected at opposite points in screw-couplings to the three-way cock B. A second water-pipe, C', leads from the lower part of the casing B' of the cock B to the faucet E. An overflow-pipe, F, leads in the usual manner from the upper part of the basin A and communicates with the upper part of the casing B'. The valve-spindle B² of the cock B is connected by a crank-rod, d, with a vertically-guided handle-rod, d', the different positions of the handle-rod setting the cock B into different positions.

The cock B is provided at its circumference with two segmental recesses, e e', the recess e serving to establish the connection between the supply-pipe C and the pipe C', while the recess e' serves for establishing connection between the discharge-pipe D and the discharge-opening b at the bottom of the top of the casing B' and bottom of the basin.

A channel, e², of the cock B communicates with the overflow-pipe F, said channel opening into the recess e', so as to conduct the overflow to the discharge-pipe D, as shown in Fig. 5.

When the handle-rod d' is forced down as

far as it will go, the cock B establishes communication between the supply-pipes C C', 55 while closing at the same time the top opening, f, communicating with the wash-basin, as shown in Fig. 2. When the wash-basin is supplied with water, the handle-rod d' is raised partly and the cock B placed in the position shown in Fig. 3, whereby the water-supply is cut off. If the handle-rod is raised still more, the cock B is placed in the position shown in Fig. 4, so that the water can pass off from the wash-basin to the discharge-pipe D. When the cock B is in the position shown in Fig. 2, the overflow-pipe F communicates by the channel e² with the discharge-pipe, as shown in Fig. 5, so that no overflow can take place. In all the different positions of the three-way cock the sewer-gas is prevented from passing to the room, and the supply and discharge of the water accomplished in a very simple, reliable, and comparatively inexpensive manner.

Having thus described my invention, I claim as new and desire to secure by Letters Patent—

The combination, substantially as set forth, of a basin or receptacle provided with an outlet-pipe, a cock connected to said outlet-pipe, 80 a water-supply pipe connecting said cock with the source of supply, a water-supply pipe connecting said cock with said basin, a waste-pipe leading from said cock for carrying off the waste water, an overflow-pipe connecting 85 said cock with said basin, and mechanism for actuating said cock, the plug of said cock being provided with a recess or channel, e, for connecting said supply-pipes, with a recess or channel, e', for connecting said outlet and waste 90 pipes, and with a channel, e², for connecting the recess last mentioned with the overflow-pipe, said plug serving in one position to disconnect and close all said pipes, in another position to connect said supply-pipes and disconnect said 95 waste and outlet pipes, closing the latter, and to connect said overflow and waste pipes, in a third position to disconnect said supply-pipes and connect said outlet and waste pipes.

In testimony that I claim the foregoing as my invention I have signed my name in presence of two subscribing witnesses.

JOSEPH JUNGBLUTH.
